AUDIO FREQUENCY AMPLIFIER

Ernest S. Lundie, Haddon Heights, N. J., assignor
to Radio Corporation of America, a corporation
of Delaware

Application November 30, 1939, Serial No. 306,955

1 Claim. (Cl. 179—171)

The present invention relates to a. f. amplifiers, and has for its object to provide an improved a. f. amplifier circuit and means whereby the amplifier gain and frequency characteristic may be controlled effectively.

It is also an object of the present invention to provide an a. f. amplifier having an improved tone control circuit embodying inverse feedback without resorting to variable loading means for the signal conveying circuits as is the case with the usual type of tone control system.

It is a still further object of the present invention to provide an improved control system for an a. f. amplifier stage whereby the frequency characteristic of an amplifier may be varied at the high and low frequency ends thereof through a single control circuit in connection with said stage without interaction with volume control means in the same stage.

The invention will, however, be better understood from the following description when considered in connection with the accompanying drawing, and its scope is pointed out in the appended claim.

In the drawing,

Figure 1 is a schematic circuit diagram of an a. f. amplifier embodying the invention.

Figure 2 is a similar schematic circuit diagram of a portion of the amplifier shown in Fig. 1 illustrating a modification of the invention, and

Figure 3 is a graph showing the curves illustrative of certain operating characteristics of the circuits of Figs. 1 and 2.

Referring to Fig. 1, 5 is a first stage a. f. amplifier tube provided with a signal input circuit 6—7 and an output circuit 8—9 coupled to a volume control potentiometer 10 through a coupling capacitor 11.

The volume control contact 12 is connected through a limiting resistor 13 and a lead 14 to the control grid 15 of a second stage amplifier tube 16. The lead 14 is also coupled through a limiting resistor 17 and a lead 18 to a second volume control potentiometer 19 having input terminals, one of which is common with the input terminal 7 and the other of which is indicated at 20.

With this arrangement, dual volume control is provided on the stage 16. Signals may be received on the grid 15 from input terminals 6—7 through the input stage 5 or directly from input terminals 7—20. By adjusting the potentiometer devices 12 and 19, signal mixing from the two signal sources may be effected.

A self-bias resistor 21 in circuit with the cathode 22 of the said tube 16 provides biasing potential for the grid 15. With an amplifier tube of the type 6J7 at 16, the self-bias resistor 21 may be of the order of 1000 ohms. The input circuits and preceding amplifier 5 are representative of any suitable input circuit arrangement for the

amplifier stage 16 which includes suitable volume control means for regulating or adjusting the strength of the signal applied to the control grid 15.

5 The input circuit arrangement of the amplifier stage 16 further includes a tone control network 23 having a feedback connection 24 with the output circuit 25 of a succeeding amplifier stage 26. The latter is coupled through suitable means 27 with the output circuit 28 of the amplifier stage 16, so that a feedback loop is provided through the stages 16 and 26. With the feedback connection between the output circuit of the stage 26 and the cathode terminal 29 of the preceding stage 16, the feedback is degenerative.

The external portion of the feedback circuit includes a limiting resistor 30, a high frequency control path comprising a series resistor 31 and a shunt capacitor 32 therefor, a low frequency control path comprising a variable resistor having a resistor element 33 and a variable contact 34 together with a shunt bypass capacitor 35. The resistor 30 and the tone control means or control paths are connected serially in the order named 20 and as shown, between the output circuit connection 24 and the cathode connection 29 on the self-bias resistor 21. The latter connection includes a switch having a movable contact 36 and two fixed contacts 37 and 38, the contact 37 being included in the feedback circuit and the contact 38 being connected to a relatively large bypass capacitor 39 which is placed in shunt with the self-bias resistor 21 when the switch is closed to the contact 38. This capacitor provides the usual low impedance bypass at signal frequencies.

In the position shown, the switch is closed to complete the feedback circuit to the cathode and at the same time replaces the shunt capacitor 39 for the self-bias resistor 21 with a bypass circuit comprising two resistor or impedance elements 40 and 41 serially connected, the latter being in the form of a potentiometer having a contact 42 which is connected to the low potential terminal of the resistor 41 through a bypass or tone control capacitor 43.

This provides a second high frequency control path connected in shunt with first high frequency control path and the low frequency control path between the feedback point 29 on the cathode 22 and the common circuit return path or ground.

50 The output circuit 25 of the amplifier stage 26 may be coupled to any suitable load device, such as a loudspeaker indicated at 45 through coupling means provided, in the present example, by a transformer 46.

In one embodiment of the invention, the tone control circuit comprises a resistor 30 of substantially 82000 ohms, a capacitor at 32 of 820 mmf. shunting the resistor 31 of 470,000 ohms, while the capacitor 35 has a value of the order of .01

mf. and the maximum resistance of the resistor 33 being of the order of 2-4 megohms. In the shunting circuit for the self-bias resistor 21, the resistor 40 has a resistance of substantially 100 ohms, while the resistor 41 is substantially 5000 ohms maximum. The capacitors 39 and 43 may have values of 20 and .35 mf., respectively.

The operation of the system may be considered in connection with the curves shown in Fig. 3, to which attention is now directed along with Fig. 1.

With the switch 36 closed to the contact 38, the inverse feedback circuit is disconnected and the self-bias resistor 21 is shunted by a relatively low impedance path comprising the capacitor 39, rendering operation of the input circuit of the amplifier substantially normal and providing a relatively high gain and uniform output over a relatively wide *a. f.* range, as indicated by the curve 50 in Fig. 3. Thus, a high normal uniform response may be provided by the amplifier by closing the switch to the contact 38.

When tone control or variation of the frequency characteristic of the amplifier is desired, the switch is closed to the position shown, thereby removing the bypass capacitor 39 from the circuit and completing the feedback circuit from the output connection 24 to the cathode 22, thus reducing the gain of the amplifier to a lower level, as indicated by the curve 51-52-53 which represents substantially a flat response characteristic of lower amplitude level.

With the contact 34 moved to the lowermost position, as viewed in the drawing, thereby reducing to substantially zero the resistance in circuit of the resistor section 33, and disregarding the shunting effect of the capacitor 32, the inverse feedback current from the output connection 24 is limited by the resistor 31 and the series controlling resistor 30 which also prevents loading of the output circuit 25. The amount of feedback applied to the cathode 22 of the driver stage 16 is such that substantially uniform gain over the *a. f.* range is provided. This is assuming also that the contact 42 is adjusted to the lowermost position on the resistor 41 thereby removing from the shunt circuit for the cathode resistor 21 the shunting effect of the capacitor 43.

By connecting the capacitor 32 in shunt with the series control resistor 31, that is, across a portion of the series resistance comprising the resistors 30 and 31, additional feedback voltage is provided at the high frequency end of the amplifier range, causing a reduction in the gain of the amplifier in that range and resulting in a response characteristic for the amplifier as indicated by the portion of the curve shown at 54 in Fig. 3. The impedance of the capacitor 32 with respect to the resistance of the resistor section 31 is such that the desired high frequency attenuation is obtained, and the high frequency control paths constituted by the capacitor 32 and resistor 31 may remain fixed thereafter.

The predetermined high frequency response established in the path 31-32 may now be varied by operation of the contact 42 on the potentiometer 41 which is at the ground or cathode end of the feedback circuit, to gradually shunt the resistance of the potentiometer by the capacitor 43, thereby permitting the feedback energy at the higher frequencies to be bypassed around the cathode resistor 21 across which the feedback potentials are applied to the input circuit of the stage 16. The capacity of the capacitor 43 is

such that, when fully shunted across the potentiometer 41, the high frequency response characteristic may be restored to a level as shown at 51.

5 The resistor 40 serves as a limiting resistor in the high frequency variable control path to prevent the response characteristic from rising to a higher value than is desired, such as that indicated at 51. Thus, the high frequency tone 10 control circuit comprises a high frequency control path containing fixed elements 31-32 for establishing a lower limit or level in the high frequency response characteristic and a variable high frequency control path 41-42-43, together 15 with the limiting resistance 40 for establishing an upper limit or level for the response characteristic, between which and the lower limit a variable control range is provided. As hereinbefore noted, the variable control is placed at the ground end of the feedback circuit, as is desirable, and permits the control elements to be placed remotely as desired without regard for extensive shielding.

Considering now the low frequency tone control means in the stage 16, the capacity value of the capacitor 35 is such that it offers an appreciable impedance to feedback energy in the lowermost portion of the operating range of the amplifier and is gradually made effective in the 20 circuit or adjusted to a desired effective value, by operation of the contact 34 to vary the value of the resistor 33. As the contact 34 is moved upwardly as viewed in the drawing to increase the value of the resistance 33 in shunt with the 25 capacitor 35, the normal low frequency feedback characteristic 53, as established by the limiting resistors 30 and 31 hereinbefore referred to, is reduced because of the impedance inserted in circuit, resulting in a rise in the low frequency response characteristic as indicated by the portion 30 55 of the curve in Fig. 3, the relative impedance values of the capacitor 35 and resistor 33 in the feedback circuit determining the upper limit to which the curve 55 rises. Thus, by varying the 35 resistor 33, the low frequency response of the amplifier may also be varied between limits such as indicated by the curves 53 and 55, and tone control for the low frequency end as well as the high frequency end is provided in the same circuit without interaction. By applying the tone control to the cathode circuit, variable gain or volume control at 12 and 19 may be included in the input circuit of the tone controlling amplifier stage.

55 From the foregoing, it will be seen that high and low frequency tone control feature is provided by inverse feedback as distinguished from the usual loading circuits. The feedback circuit employed includes a fixed high frequency control path, together with a limiting impedance effective over the full frequency range, a low frequency control path variably controllable, and a high frequency variable control path including a limiting impedance, the first-named high frequency control path serving to limit the lower end of the attenuation range for high frequencies and the series impedance element in the variable path serving to limit the upper end of the attenuation range for high frequencies.

In certain amplifiers, it is desirable to provide a wider range of control of the high and low frequency ends of the amplifier operating range for tone control purposes. For example, it is desirable to extend the control range between the curves 54 and 51 to a wider range including a

characteristic indicated by the curve 56, so that, for certain operating conditions, high frequency tone accentuation may be obtained.

Likewise for the low frequency end of the operating range, it may be desirable to suppress the low frequency response to provide a characteristic as indicated by the curve 57, the full operating range then being between the curves 55 and 57.

A modification of the circuit of Fig. 1 for the purposes above mentioned is shown in Fig. 2 to which, along with Fig. 3, attention is now directed and in which like reference numerals are applied to like circuits and circuit elements as in Fig. 1. The amplifier tube 16 is provided with a cathode resistor 21 having the cathode terminal 29 to which inverse feedback potentials are applied from the output circuit 25 of the second stage amplifier 26 through a suitable connection 24, and an inverse feedback circuit including the series-controlling resistor 30-31, the latter portion of which is shunted by the high frequency controlling capacitor 32. The low frequency controlling capacitor is indicated at 35, and the series-connected resistors 40A and 41 as two series-connected elements being in shunt with the cathode resistor 21. The high frequency variable control path also includes the capacitor 43 connected with the potentiometer contact 42 for the resistor 41. The function and the operation of the circuit elements thus far referred to is the same as described for the circuit of Fig. 1.

However, in the present circuit, the high frequency tone control includes the resistor 40A as a variable or adjustable element. This may be adjusted to substantially zero resistance, in which case, as the resistance approaches zero, the shunting effect of the capacitor 43 is rendered more complete across the cathode resistor 21 as the contact 42 is moved in an upward direction as viewed in the drawing, thereby substantially reducing the high frequency feedback to zero and permitting the high frequency response of the amplifier to rise to a higher limit as indicated by the curve 56. Thus the upper limit of the attenuation range of the high frequency variable tone control means may be adjusted by adjusting the value of the series resistor element 40A.

In the present example, with the circuit elements having values as previously referred to, when the resistor 40A is adjusted to substantially 100 ohms, the frequency characteristic of the amplifier at the high frequency end is made substantially flat as shown by the curve 51, when the resistor 41 is shunted by the capacitor 43.

The effectiveness of the low frequency control capacitor 35 is the same as in the circuit previously described in that it offers an appreciable impedance to the feedback energy in the low frequency end of the operating range of the amplifier thereby reducing the feedback and permitting a higher gain in the amplifier in that range, as shown by the curve 55. In order to carry this response characteristic not only to the normal flat characteristic indicated by the curve portion 53 but also to attenuate the low frequency output of the amplifier to extend the low frequency tone control range, the low frequency feedback control path constituted by the capacitor 35 is provided with a variable control resistor 60 connected to take feedback voltage from a terminal 61 at the input end of the limiting resistor 31 through an inductive reactance or choke

coil 62. The resistor 60 is further connected with the cathode side of the capacitor 35, as indicated at 63 in a path 64 shunting not only the capacitor 35 but the capacitor 32, as the feedback control is thereby rendered more effective at lower frequencies than that permitted by the impedance of high frequency control path 31-32.

The reactance of the choke coil 62 is such that the path 64 provides no appreciable conductive circuit for feedback energy in the higher frequency range or midrange of the frequency characteristic of the amplifier, but is of relatively low impedance to feedback currents in the low frequency end of the operating range of the amplifier. Therefore, as the value of the resistance 60 in circuit is decreased, the low frequency feedback voltage is further increased, causing a reduction in the gain of the amplifier in the low frequency range, as indicated by the curve 53 and permitting the feedback to be further increased to a value such that the amplifier gain is appreciably attenuated in the low frequency range along a response curve indicated at 57.

It will be seen that the low frequency control path constituted by the reactance 62 and the variable resistor 60 in the circuit 64 provides a branch feedback path from the terminal 61 to the cathode terminal 29 independently operable to reduce the low frequency response of the amplifier from that indicated at 55 and determined by the value of the capacitor 35 as an upper limit of the attenuation range, and the curve portion 57 which may be any desired lower limit of the attenuation range.

From the foregoing, it will be seen that the high and low frequency tone control ranges as provided by inverse feedback may be extended to provide not only high and low frequency attenuation but a rise in the high and low frequency response characteristic of the amplifier, as may be desired for any particular amplifier. It will further be seen that, by breaking the feedback circuit to the cathode and connecting a path of relatively low impedance, at signal frequencies, across the cathode, resistor, the amplifier gain may be restored to normal without complicated switching.

I claim as my invention:

50. In an amplifier, the combination of an amplifier stage having an output circuit, means providing a feedback connection with said circuit terminating in a preceding amplifier stage, a high frequency control path in said connection including a limiting resistance and shunt capacity for at least a portion thereof effective to increase the inverse feedback in a higher frequency range, a low frequency control path serially in circuit with said first-named path having a relatively high impedance at a predetermined lower frequency range and including a capacitor of relatively low impedance with respect to the first-named capacitor and of relatively high impedance in a predetermined low frequency range 60 and a variable shunt resistance element, a cathode circuit for said preceding amplifier stage having an impedance element serially in circuit with said first and second-named frequency-controlling paths, a capacitor having a relatively low impedance in a frequency range corresponding to the high frequency end of the operating range of said amplifier, and means for variably connecting said capacitor in shunt with at least a portion of said last-named impedance element.

ERNEST S. LUNDIE.
